UNITED STATES PATENT OFFICE.

THOMAS G. RAMSEY, OF WAPANUCKA, OKLAHOMA.

ADJUSTABLE WINDOW-SHADE BRACKET.

1,258,242.

Specification of Letters Patent.

Patented Mar. 5, 1918.

Application filed September 11, 1916. Serial No. 119,521.

To all whom it may concern:

Be it known that I, THOMAS G. RAMSEY, a citizen of the United States, residing at Wapanucka, in the county of Johnston and State of Oklahoma, have invented certain new and useful Improvements in Adjustable Window-Shade Brackets, of which the following is a specification.

This invention relates to adjustable window shade brackets and the primary object is to provide a bracket for supporting the ends of a shade roller that will be adapted to be vertically adjusted for raising or lowering the shade roller and laterally adjusted for accommodating various lengths of shade rollers.

The above and additional objects are accomplished by such means as are illustrated in the preferred embodiment and in the accompanying drawings, wherein like characters denote like or corresponding parts throughout the several views, in which:—

Figure 1 is a fragmentary elevation of a window frame showing all of my brackets applied thereto.

Fig. 2 is a section on the line 2—2 of Fig. 1.

Fig. 3 is a section on the line 3—3 of Fig. 1.

Referring to the drawing, wherein is illustrated the preferred form of my invention, and in which like numerals of reference indicate corresponding parts throughout the several views, it has been thought advisable to disclose only one of the brackets since they are designed to be used at either side of the window frame for supporting either end of a shade roller. I therefore provide a channel bar 1 having a dovetail groove 2 extending for its entire length. The ends of the bar 1 are fastened by screws to the frame A of the window and the dovetail channel 2 receives the tongue 3 of a supporting bar 4 which depends vertically from the tongue 3. A locking screw 5 is extended through an opening 6 in the tongue 3 and has its end extended beyond the tongue and adapted to register with any one of a plurality of recesses 7 formed in the bar 1.

Laterally projecting side flanges 8 are integrally formed with the supporting bar 4 thereby providing a channel 9 between the flanges for receiving the adjusting head 10 which carries a trunnion keeper 11 for re-

ceiving the trunnions of a shade roller. The flanges 8 as shown by Fig. 3 of the drawing are provided with the grooves 12 which communicate with the channel 9 thereby providing a T-shaped slot 13. Tongues 14 are integrally formed with the sides of the head 10 and slidably fit within the grooves 12 so that the head is prevented from being accidentally displaced and is free to be adjusted vertically. For holding the head 10 in adjusted position a locking screw 15 is extended through an opening in the head and is adapted to register with any one of a plurality of depressions 16 formed in the bottom of the slot 13.

From the foregoing it will be observed that a very simple and durable adjustable window shade bracket has been provided, the details of which embody the preferred form. I desire it to be understood however, that slight changes in the minor details of construction may be made without departing from the spirit of the invention or the scope of the claims hereunto appended.

I claim:

1. A shade roller bracket comprising a horizontal bar having a longitudinal channel formed therein and provided with a plurality of recesses longitudinally spaced apart, a vertical bar having its upper end provided with a tongue extending at right angles, the said vertical bar depending from the center of the said tongue, the said tongue being shaped to fit within the said channel for sliding movement longitudinally of the horizontal bar, retaining screws extending through the end of the said vertical bar and through the said tongue and adapted to be received in any of the said recesses, shade roller engaging means mounted on the said vertical bar and including a head slidably mounted on the vertical bar and provided with a locking screw engageable with the said vertical bar, the said head being slidably mounted to permit adjustment of the said means vertically of the said bar.

2. A shade roller bracket comprising a horizontal bar and a vertical bar, the horizontal bar having a longitudinal channel, a tongue formed on the vertical bar and received in the said channel to permit horizontal adjustment of the said bar, each of the said bars having recesses formed therein,

a screw extended through the said bar at its upper end and engageable with the recesses in the said horizontal bar, a pair of flanges extending from opposite longitudinal edges 5 of the said vertical bar, a head extending between the flanges and slidably movable on the said bar and provided with a locking screw adapted to be received in any of the

said recesses, and a trunnion engaging element carried by the said head. 10

In testimony whereof I affix my signature in presence of two witnesses.

THOMAS G. RAMSEY.
